CLAIM

We claim the ornamental design for a heated label tongs, as shown and described.

DESCRIPTION

FIG. 1 is a perspective view of a heated label tongs incorporating our new design;

FIG. 2 is a side elevational view thereof, the other side elevational view being a mirror image of that shown;

FIG. 3 is a front elevational view thereof,

FIG. 4 is a rear elevational view thereof; and,

FIG. 5 is a top elevational view thereof, the bottom elevational view being a mirror image of that shown.
